UNITED STATES PATENT OFFICE.

EMMIT G. LATTA, OF SYRACUSE, NEW YORK.

TYPE-WRITING MACHINE.

1,273,882.

Specification of Letters Patent. Patented July 30, 1918.

Application filed August 18, 1915. Serial No. 46,063.

To all whom it may concern:

Be it known that I, EMMIT G. LATTA, a citizen of the United States, residing at Syracuse, in the county of Onondaga and 5 State of New York, have invented a new and useful Improvement in Type-Writing Machines, of which the following is a specification.

This invention relates more particularly 10 to front-strike typewriting machines of that kind in which the type-bar segment or support, instead of the platen, is shifted for printing different case characters, the object of the invention being to provide an efficient and practical universal bar mechanism 15 for such machines in which the type-bars act directly on the universal bar and produce like action thereof in the different printing positions of the type-bars, and to accomplish 20 this by means which are as simple and capable of as rapid operation as universal bar mechanisms used in machines in which the platen is shifted for different case printing.

In the accompanying drawings: 25 Figure 1 is a fragmentary transverse sectional elevation of a typewriting machine embodying the invention, showing four of the type-bars in place.

Fig. 2 is a sectional elevation thereof on 30 line 2—2, Fig. 1.

Figs. 3 and 4 are corresponding views, less complete, of a slightly modified construction.

Figs. 5 and 6 are similar views of another modification.

The drawings illustrate a portion of a front strike typewriting machine in which A represents the stationary main frame, a the rigidly secured top plate thereof, B the platen, C the type-bars and D the segment 40 or support on which the type-bars are pivotally mounted to swing upwardly and rearwardly to make the impressions at the front side of the platen. The platen is journaled in a carriage of any suitable 45 construction arranged to travel in letter spacing direction on a suitable stationary guide or track, such as shown at b, on the top plate a of the frame. b' b² represent two adjustable track bars which are 50 mounted to travel on anti-friction balls on the track b and carry the various parts of the carriage which, for the sake of simplifying the drawings, are not shown.

As shown in the drawings, the type-bars 55 are pivoted by a wire d in slots d' in the segment D but they could be pivotally

mounted on the segment by separate hangers, such as commonly employed, or in any other suitable way, and any suitable kind of plain or anti-friction bearings for the 60 type-bars can be used.

The segment is suitably mounted in the machine to shift up and down for placing one or another of the different sets of type on the type-bars in printing relation to the 65 platen. As shown, the segment is provided with lugs e pivoted to the front ends of arms E projecting forwardly from a rock shaft F which is journaled on the main frame and is adapted to be rocked by suitable means 70 (not shown) for shifting the segment from one to the other of its different operative positions. Anti-friction balls g working in grooves g' in the ends of the segment and in grooves g² in the sides of the main frame 75 co-operate with the rock arms E in holding the segment upright and guiding it in its vertical movements.

H, Figs. 1 and 2 represents a universal bar which is curved on a radius adapting it to 80 stand upright above the pivoted ends of the type-bars in position to be struck and moved by projections or parts h on the pivot ends of the type-bars when the type-bars approach the platen. Preferably the universal 85 bar consists of a sheet metal stamping of crescent-like shape, decreasing in width toward its ends and having stiffening flanges h' projecting from the inner and outer edges thereof. The universal bar is supported 90 from the fixed frame of the machine so as to move substantially horizontally or perpendicularly to the direction in which the segment shifts, preferably by rigid arms i which project substantially horizontally 95 from the bar and each of which is pivoted to a pair of parallel swinging links i' and i² arranged one in rear of the other. The two links i' are fixed to and depend from a horizontal rock shaft I, and the other links i² are preferably secured to and depend from a second rock shaft I'. These rock shafts are suitably journaled parallel with each other on the underside of the top plate a. The universal bar is thus adapted to move 100 substantially horizontally or perpendicularly to the plane in which the type-bar pivots are located, and is always maintained parallel with such plane, and, as shown, the bar is arranged so that its front face moves 105 from a plane in front of the plane of the type-bar pivots to a plane in rear thereof.

The two positions of the segment and of the universal bar are indicated by full and broken lines in Fig. 2, and the two positions of the segment are similarly indicated in Fig. 1. The universal bar is wide enough to be struck by the projections h on the type-bars in both positions of the segment and as all of the type-bars have the projections h at the same distance from their fulcrums they effect like movements of the universal bar in both positions of the segment. The projections on the four type-bars indicated in Fig. 1 strike the universal bar at the points marked 1 when the segment is in lower case position, and at the points marked 2 when the segment is shifted to upper case position. The remaining bars of the series will strike at correspondingly related points on the universal bar. This arrangement enables the type-bars on a shiftable segment to actuate the universal bar with the same uniformity and speed that has heretofore been attained with type-bars mounted on a fixed segment, and the simple ribbon vibrator and other advantages pertaining to the shifting segment construction are obtained with a universal bar actuated by the direct impact of the type-bars.

K represents the carriage escapement and L the ribbon vibrator, both of which are actuated by the universal bar. These devices may be constructed and operatively connected to the universal bar in any suitable way. As shown, the rock shaft I is provided with a rearwardly projecting arm k connected to a link k' which trips the escapement, and a forwardly projecting arm l connected by a link l' and lever l'' to the ribbon vibrator. The ribbon vibrator has a rearwardly bent lower end entering a notch in the front end of the vibrator lever l'' and is guided, as usual, by the rear face of the center guide M for the type-bars which has a rearwardly bent lower portion m secured to the underside of the top plate a , and a down-turned rear end that supports the pivot m' for the vibrator lever l'' .

The construction shown in Figs. 3 and 4 is substantially the same as that above described except that the type-bars have flat-faced lugs h'' and strike forwardly projecting edge flanges h'' on the universal bar H'.

Figs. 5 and 6 show a universal bar H² arranged to be struck on its edge by the type-bars, which are made with a straight inner edge portion h'' long enough to strike the universal bar in both positions of the segment. These straight edge portions h'' are made so that they will be parallel with the plane of the front edge of the universal bar when the type-bars are at the printing point or in contact with the platen, as indicated in Fig. 6, thus causing the type-bars to move the universal bar back the same dis-

tance in both positions of the segment notwithstanding the fact that the type-bars engage the universal bar at different distances from their fulcrums in the two positions of the segment.

The universal bars in the two modified constructions shown in Figs. 3 and 4 and Figs. 5 and 6 are supported from the stationary frame of the machine, as explained in connection with the first construction described.

Obviously the construction shown in Figs. 1 and 2 is adapted for use with a shifting segment having three operative positions, by making the universal bar of greater width and locating the projections h farther from the fulcrums of the type-bars. The construction shown in Figs. 3 and 4 can also be used with a segment having three operative positions by making it of the necessary width and providing it with a third forwardly projecting rib between the two edge ribs or flanges and locating the projections h'' of the type-bars farther from their fulcrums. To adapt the construction shown in Figs. 5 and 6 for machines in which the segment shifts to two positions from normal, it is only necessary to raise the universal bar and lengthen the straight edge-portion h'' of the type-bar; or in case the segment shifts both up and down from the normal position it is only necessary to lengthen the straight edge h'' of the type-bar.

The described constructions cause the type-bars to strike the universal bar a smart blow when at their greatest speed of travel just before they strike the platen, and thus avoid the friction and sluggish action of a camming contact.

I claim as my invention:

1. In a typewriting machine, the combination with a series of upwardly and rearwardly swinging type-bars pivotally mounted in an arc, and a common shiftable support for placing the type-bars in different case printing positions, of an arc-shaped universal bar of smaller radius than the arc of the type-bar pivots mounted on a stationary part of the machine in position to intercept the type-bars substantially in the plane of their pivots in both their normal and shifted positions.

2. In a typewriting machine, the combination with a series of upwardly and rearwardly swinging type-bars pivotally mounted on a common curved support which is shiftable to place the type-bars in different case printing positions, and a platen, of a curved universal bar mounted independently of said support to intercept the type-bars in both their normal and shifted positions substantially in the plane of their pivots and to be moved by the type-bars in a direction substantially at right angles to said plane.

3. In a typewriting machine, the combi-

- nation with a series of type-bars pivotally mounted in an arc on a common segmental support which is shiftable for placing the type-bars in different case printing positions, of a universal bar curved on a smaller radius than that of the arc of the type-bar pivots and supported independently of said segment between the same and the printing point and maintained in planes parallel with the plane of the type-bar pivots at all times, and to be moved by the type-bars substantially the same in both their normal and shifted positions.
4. In a typewriting machine, the combination with a series of type-bars, and a segment on which the type-bars are pivoted in an arc and which is shiftable in a direction substantially parallel with the plane of the type-bar pivots for placing the type-bars in different case printing positions, of a universal bar which is curved substantially parallel with the arc of the type-bar pivots and is supported independently of said segment between the type-bar pivots and the printing point in a plane substantially parallel with the plane of the type-bar pivots and in position to be struck by the type-bars in the last portion of their travel and to be moved thereby in a direction substantially perpendicular to said plane.
5. In a typewriting machine, the combination with a series of upwardly and rearwardly swinging type-bars, and a support therefor which is shiftable for placing the type-bars in different case printing positions, of a curved universal bar and a device which is actuated thereby at the type strokes both mounted independently of the type-bar support with the universal bar substantially parallel with the arc of the type-bar pivots and in position to be struck and actuated by the type-bars when in both their normal and shifted positions.
6. In a typewriting machine, the combination with a series of upwardly and rearwardly swinging type-bars, a common support therefor on which the type-bars are pivoted in an arc and which is shiftable for placing the type-bars in different case printing positions, and a stationary main frame, of a curved universal bar located substantially in the plane of the type-bar pivots and a device which is actuated thereby at the type-strokes both mounted on the main frame independently of the type-bar support with the universal bar in position to be actuated by the type-bars when in both their normal and shifted positions.
7. In a typewriting machine, the combination with a series of type-bars, and a common supporting segment therefor on which the type-bars are pivoted in an arc which is shiftable for placing the type-bars in different case printing positions, of a segmental universal bar mounted independently of said segment substantially in the plane of the type-bar pivots in position to be moved by the type-bars in both their normal and shifted positions, the relative construction and arrangement of the type-bars and universal bar causing equal movements of the universal bar in the different positions of the type-bars.
8. In a typewriting machine, the combination with a series of pivoted type-bars, and a supporting segment therefor which is shiftable for placing the type-bars in different case printing positions, of a segmental universal bar mounted independently of said segment between the type-bar pivots and the printing point in position to be struck by the type-bars in the last portion of their travel when in both their normal and shifted positions and at the same distance from their fulcra.
9. In a typewriting machine, the combination with a series of type-bars, and a common supporting segment therefor on which the type-bars are pivoted in an arc and which is shiftable for placing the type-bars in different case printing positions, of a segmental universal bar of smaller radius than the arc of the type-bar pivots mounted independently of said segment in position to be struck and moved by the type-bars and being of a width sufficient to be struck by the same part of the type-bars in the different positions thereof.
10. In a typewriting machine, the combination with a series of type-bars each provided with a projection, and a supporting segment for the type-bars which is shiftable for placing the type-bars in different case printing positions, of a segmental universal bar mounted independently of said segment in a substantially fixed location between the type-bar pivots and the printing point and being of a width to be struck by said projections in the different positions of the type-bars.
11. In a typewriting machine, the combination with a series of type-bars, and a supporting segment on which the type-bars are pivoted and which is shiftable for placing the type-bars in different case printing positions, of a segmental universal bar mounted independently of said segment in position to be struck by the type-bars at substantially equal distances from their pivots in both their normal and shifted positions, said universal bar having stiffening flanges at its inner and outer edges.
12. In a typewriting machine, the combination with a series of type-bars, and a segment on which all of the type-bars are pivoted and which is shiftable for placing the type-bars in different case printing positions, of a curved universal bar mounted independently of said segment in position to be moved by the type-bars in both their

normal and shifted positions, said universal bar being moved by the type-bars from a position at one side of the plane of the type-bar pivots to a position at the opposite side 5 of said plane.

13. In a typewriting machine, the combination with a series of type-bars, and a segment on which the type-bars are pivoted and which is shiftable in a direction substantially 10 parallel with the plane of the type-bar pivots, of a curved universal bar which is supported independently of said segment between said type-bar pivots and the printing point in a plane substantially parallel with 15 the plane of the pivots and is moved by the type-bars in a direction substantially perpendicular to such plane.

14. In a typewriting machine, the combination with a series of type-bars, and a segment 20 on which the type-bars are pivoted, in an arc and which is shiftable in a direction

substantially parallel with the plane of the type-bar pivots for placing the type-bars in different case printing positions, of a universal bar which is supported independently 25 of said segment between the type-bar pivots and the printing point in position to be struck and moved by the type-bars in a direction substantially perpendicularly to said plane, said type-bars having parts arranged 30 to strike said universal bar at points disposed in different arcs when the type-bars are in different case printing positions each of which arcs is substantially parallel with the 35 arc of the type-bar pivots in one position of the segment.

Witness my hand this 16th day of August, 1915.
